Primary Examiner — Wan Laymon(57) **CLAIM**

The ornamental design for a surgical instrument handle, as shown and described.

DESCRIPTION

FIG. 1 is a perspective view of a surgical instrument handle, illustrating our new design.

FIG. 2 is a first side elevation view thereof;

FIG. 3 is a second side elevation view thereof;

FIG. 4 is a top plan view thereof;

FIG. 5 is a bottom plan view thereof; and,

FIG. 6 is a detail view thereof within line 6 of FIG. 1.

The broken lines in the drawings illustrate optional environmental features that form no part of the claimed design.
